PATENTED MAR. 5, 1907.

R. L. CRAIN.

MACHINE FOR FORMING FLEXIBLE BANDS ACROSS SHEETS OF PAPER.

APPLICATION FILED OCT. 8, 1906

UNITED STATES PATENT OFFICE.

ROLLA L. CRAIN, OF OTTAWA, ONTARIO, CANADA.

MACHINE FOR FORMING FLEXIBLE BANDS ACROSS SHEETS OF PAPER.

No. 846,011.

Specification of Letters Patent.

Patented March 5, 1907.

Application filed October 8, 1906. Serial No. 338,032.

To all whom it may concern:

Be it known that I, ROLLA L. CRAIN, of the city of Ottawa, in the county of Carleton, Province of Ontario, Canada, have invented 5 certain new and useful Improvements in Machines for Forming Flexible Bands Across Sheets of Paper, of which the following is a specification.

My invention relates to a machine for treating sheets of paper to be used in loose-leaf binders for the purpose of rendering an integral portion or band of each sheet more flexible than the remainder, whereby when the binder is opened the sheet will bend along 15 this band and lie flat against the cover.

The general object of the invention is to provide a machine of this character which will operate with great rapidity and will not in any way mar the sheets of paper passing 20 therethrough.

The specific object of the invention is to provide a machine for quickly and economically carrying out the improved method of treating sheets of paper for the purpose above 25 specified, which I have described in an earlier application and which consists in forming a parallel series of corrugations across a portion of the sheet, then reversing the corrugations and flattening the sheet.

In the embodiment illustrated the above 30 operation is carried out by passing the sheets through three sets of rollers, the first set forming a series of corrugations, the second set reversing the corrugations, and the third 35 set smoothing them out, the details of the construction being more fully set forth and described in the accompanying specifications and drawings.

Figure 1 is a top view of my improved machine. Fig. 2 is a side view of the same. Fig. 3 is a sectional view along the line 2 2, Fig. 1. Fig. 4 is an enlarged sectional detail taken along the line 3 3, Fig. 2. Fig. 5 is an 45 enlarged sectional detail of the first set of rollers.

In the drawings like letters of reference indicate corresponding parts in each figure.

Referring to the drawings, A is the frame, of any suitable or desirable construction, that 50 shown comprising end members a and b, connected by suitable bars c.

B, C, and D are three sets of rollers. The top rollers d, e, and f are fixed in position and have pintles on the ends thereof journaled in 55 suitable bearings g, secured to the frame. The lower rollers of each pair h, i, and j are

supported with freedom of movement in a vertical direction, the means I have shown to accomplish this result comprising bearing-blocks k, which journal the pintles l on each 60 side of the rollers and which are slidably held in slots m in the ends of the frame. These bearing-blocks are intermittently raised and lowered for a purpose to be hereinafter specified by means of a series of cams n, secured on 65 the opposite ends of three shafts E, F, and G, journaled in suitable bearings secured to the end members of the frame. The connection between these cams and the bearing-blocks may be of any desired character; but I prefer 70 to employ the adjustable means I have shown, comprising movable standards p, having their upper ends externally screw-threaded; rollers q, having the pintles thereof journaled in the lower end of the standard p; a 75 nut r, partially screwed on the upper end, the upper face of which abuts the under surface of the bearing-block k, and a second lock-nut s below the first for locking the same in position. By means of the nut r, which protrudes beyond the end of the arm p, I am 80 able to adjust the length of said arm, and thus adjust the distance the roller shall be moved.

The standards are preferably held in position by means of arms t, secured to the framework through which the standards extend. The first set of rollers have corresponding portions of their surface corrugated, as shown in Fig. 5, the upper roller having the corrugations u V-shaped in cross-section and adapted to enter into substantially square-shaped slots v on the lower roller. These corrugations are only provided around a portion of the surface of each roller and are cut into the 85 roller and do not outwardly protrude therefrom, whereby if the smooth surface of the rollers were contacting no corrugation would be formed on the paper unless the rollers were moved closer together while the corrugated parts of the roller moved past each other. It is for this purpose that the lower 90 roller is movably held and adapted to be intermittently moved closer to the upper roller by the cam-operated means shown.

The second set of rollers C has corrugations similar to the set B, only reversed in direction, having the corrugations V-shaped in cross-section provided on the lower roller i.

The first two sets of rollers are placed such 110 a distance apart that the ordinary feeding operation of the rollers will move the sheet

from under the first set to a corresponding position under the second set by the time the corrugations in the second rollers come into position opposite to each other, whereby the 5 first corrugations formed will be completely reversed in direction.

The three sets of rollers B, C, and D and the shafts E, F, and G are all rotated from a single source of power, which may be the 10 central shaft F, having a pulley H thereon, by means of a suitable system of gear-wheels I, the details of which will be familiar to any mechanician.

J is a feeding-table secured to the frame in 15 front of the rollers a having the top surface thereof on a level with the lower surface of the upper rollers. Continuations x and y of this table extend between the sets of rollers to support the paper during passage 20 therebetween.

To feed the paper between the rollers, I provide any suitable form of feeding device K, that shown comprising a large feeding-roller 5, rotated by suitable gearing from the 25 main source of power, and a small feeding-roller 6 on top thereof supported on arms 7, which are pivoted to the side members of the frame at 8. As usual in this type of machine, a mechanism L is provided for intermittently interrupting the feeding to prevent one sheet being fed in on top of the other. As shown, this device consists of a gate-bar 9, supported from levers 10, secured to a small rocking shaft 12, which is journaled in 30 brackets 11, secured to the members a and b of the frame. This shaft 12 is rocked by means of a lever 13, secured thereto, the opposite end of which is connected by a link-bar 14 to a crank 15, secured to the end of the 35 shaft F. The levers 10 have projections 16 upwardly extending therefrom, which are connected, by means of link-bars 17, to the levers 7 intermediate of the length of the said levers. By this means when the shaft is 40 rocked the gate 9 is lowered simultaneously with the raising of the small feed-roller 6 off the large feed-roller 5.

In the operation of the device the two rollers of each set are rotated in opposite directions, and the cams on the shafts E and F are so adjusted that the lower rollers will be moved nearer the upper rollers at the same time as the corrugations thereon come opposite each other. The cam on the third shaft 55 G is adjusted to cause the rollers to move close together and press the corrugations at the moment when the ordinary feeding operation of the rollers will have moved the sheet of paper from a position between the rollers 60 C to a corresponding position between the rollers D. The sheets of paper are fed one by one by means of the feeding devices K to the set of rollers B, which will feed the paper along and being moved close together when the 65 corrugations are opposite each other will im-

press the corrugations in the paper. After impressing the corrugations the rollers are separated, allowing the paper to feed along to the next set of rollers, which are placed so far apart to have the corrugations thereof so adjusted that by the time the paper comes into position with the corrugations therebetween the corrugations in the rollers will operate thereon to reverse the corrugations therein—that is, where a corrugation in the 75 first case protruded from one side of the paper it will now protrude from the other. In a similar manner the rollers D operate to press all the corrugations out of the paper and smooth the same, leaving it with practically the same surface that it started with, but having a band thereon rendered more flexible by the stretching of the paper from one side to the other, caused by the impressing of the corrugations, their reversal, and 85 final smoothing.

It will thus be seen that I have devised an exceedingly cheap and simple form of machine for carrying out the process hereinbefore set forth. The capacity of the machine 90 is very great, as the rollers can be rotated at a high rate of speed and the sheets of paper very quickly fed therethrough. The machine is practically automatic in its operation from beginning to end, the only manual operation being the placing of the sheets on the feeding-table J, the device L controlling the feeding to such an extent that only a medium amount of care is necessary to be exercised in placing the sheets on the table. 95

It is evident that many different forms of feeding devices might be employed, and the rollers might be intermittently moved closer together by a large number of different mechanisms, the machine depending for its operation on the feature of the three sets of rollers operating successively on the sheets of paper. In some cases it may be desirable to leave the paper with the corrugations therein, and in these cases the third set of rollers D 100 may be omitted.

It will be readily understood that while I have described with great particularity of detail one specific embodiment of the invention yet the invention is not limited thereto, as certain changes may be made in the details of construction within the scope of the appended claims without departing from the spirit of the invention. 115

What I claim as my invention is—

1. An improved machine for forming flexible bands across sheets of paper consisting of means for producing corrugations on one part only of a sheet of paper combined with means for exactly reversing each individual corrugation whereby the part forming the corrugation on one side will be stretched to form the corrugation on the opposite side as and for the purpose specified. 125

2. An improved machine for forming flexi- 130

- ble bands across sheets of paper consisting of means for producing corrugations on one part only of a sheet of paper combined with means for exactly reversing each individual 5 corrugation whereby the part forming the corrugation on one side will be stretched to form the corrugation on the opposite side and means for flattening the corrugations as and for the purpose specified.
- 10 3. In a machine for forming flexible bands across sheets of paper the combination of two pairs of corrugating-rollers having corrugating means on a part only of their periphery, whereby the sheets of paper passing through 15 will be corrugated along certain given portions only, the rollers being so disposed relative to each other that the corrugating means on the second roller will exactly reverse each individual corrugation formed by the first 20 pair of rollers as and for the purpose specified.
4. In a machine for forming flexible bands across sheets of paper the combination of two pairs of corrugating-rollers having corrugating means on a part only of their periphery, whereby the sheets of paper passing through 25 will be corrugated along certain given portions only, the rollers being so disposed relative to each other that the corrugating means on the second roller will exactly reverse each individual corrugation formed by the first 30 pair of rollers, and flattening-rollers operating to smooth the paper after the second corrugating-rollers have operated thereon as and for the purpose specified.
- 35 5. In a machine for the purpose specified the combination with the two pairs of corrugating-rollers of which the second pair is adapted to reverse the corrugations formed 40 by the first of means for feeding the paper sheet by sheet to the rollers as and for the purpose specified.
- 45 6. In a machine for the purpose specified the combination with two pairs of corrugating-rollers having the corrugations in the second set reversed to those of the first, of means for moving the rollers of each set closer together during certain parts of their revolution as and for the purpose specified.
- 50 7. In a machine for the purpose specified the combination with the two sets of corrugating-rollers having the corrugations in each set reversed, of slidable blocks secured to 55 pintles on the end of one roller of each set and means for intermittently moving the said bearing-blocks closer to the opposite roller as and for the purpose specified.
- 60 8. In a machine for the purpose specified the combination with the two sets of corrugating-rollers having the corrugations in each set reversed, of slidable blocks secured to 65 pintles on the end of one roller of each set and cam-operated means for intermittently moving the said bearing-blocks closer to the opposite roller as and for the purpose specified.

9. In a machine for the purpose specified the combination of three sets of rollers and means for successively moving the rollers of each pair closer together as and for the purpose specified.

10. In a machine for the purpose specified the combination with three sets of rollers of cam-operating means for successively moving the rollers of each pair closer together as and for the purpose specified.

11. In a machine for the purpose specified the combination with the three sets of rollers of bearing-blocks secured to the lower rollers of each pair, means for slidably supporting the same, a plurality of cams and connecting means extending between the cams and the bearing-blocks whereby the same are intermittently raised and lowered as and for the purpose specified.

12. In a machine for the purpose specified the combination with a pair of rollers having a series of grooves formed in a portion of the periphery of one roller and a series of ribs in a portion of the periphery of the other roller adapted to extend into said grooves when the rollers are rotated in opposite directions, of a second pair of rollers provided with like grooves and ribs but having the rollers therein oppositely placed, and means for rotating the rollers as and for the purpose specified.

13. In a machine for the purpose specified the combination with a pair of rollers having a series of grooves formed in a portion of the periphery of one roller and a series of ribs in a portion of the periphery of the other roller adapted to extend into said grooves when the rollers are rotated in opposite directions, of a second pair of rollers provided with like grooves and ribs but having the rollers therein oppositely placed, means for rotating the rollers, and means for moving the rollers of each pair closer together during the parts of the revolution when the ribs on one roller are opposite the grooves of the other as and for the purpose specified.

14. In a machine for the purpose specified the combination with a pair of rollers having one roller provided with a series of grooves on a portion of the periphery thereof and the other roller with a series of ribs adapted to extend into said grooves when the rollers are rotated in opposite directions of a second set of rollers having grooves in one roller and ribs in the opposite roller oppositely placed to the first-mentioned rollers, the second set of rollers being placed such a distance apart that the corrugating means will operate to reverse the corrugations formed by the first rollers and means for rotating the rollers as and for the purpose specified.

15. In a machine for the purpose specified the combination with a set of rollers having corrugating means formed on a portion of their peripheries of a second set of rollers having corrugating means also formed on

- their peripheries but reversed in direction to the corrugating means on the first-mentioned rollers, the second set of rollers being placed such a distance from the first set that the corrugating means will operate to reverse the corrugations formed by the first set of rollers and means for rotating both sets of rollers as and for the purpose specified.
16. An improved machine for the purpose specified having two pairs of corrugating-rollers, the second rollers being adapted to produce a corrugation reversed in direction to the first, the corrugating means of each set of rollers only being thrown into operation when the rollers are moved closer together as and for the purpose specified.
17. An improved machine for forming flexible bands across sheets of paper consisting of two pairs of rollers having longitudinal corrugating-ribs and grooves formed on portions only of their peripheries whereby a portion only of the paper passing therethrough will be corrugated and having the same parts of the peripheries contacting and operating to feed the paper from the rollers, the two sets of rollers being placed such a distance apart that the second set will exactly reverse the corrugations formed by the first as and for the purpose specified.
18. In a machine for the purpose specified the combination with the two sets of corrugating-rollers, the second set being adapted to produce a corrugation reversed in direction to the first, of means for moving the rollers of each set closer together during certain portions of their revolution and means for adjusting the distance the said rollers are moved as and for the purpose specified.
19. In a machine for the purpose specified the combination with the two sets of corrugating-rollers having the lower rollers of each set movable, of means for intermittently moving the lower rollers closer to the upper ones and means for adjusting the distance the said lower rollers are moved as and for the purpose specified.
20. In a machine for the purpose specified the combination with the two sets of corrugating-rollers having one movable roller in each set, of means for intermittently moving the movable rollers closer to the fixed rollers as and for the purpose specified.
21. In a machine for the purpose specified the combination with the two sets of corrugating-rollers having one movable roller in each set, of means for intermittently moving the movable rollers closer to the fixed rollers and means for independently adjusting the intermittent movement of the movable rollers as and for the purpose specified.
22. In a machine for the purpose specified the combination with the two pairs of corrugating-rollers having one movable roller in each pair, of bearing-blocks journaling the movable rollers, means for slidably supporting the same, a standard having an externally-screw-threaded top, a nut screwed on said top and extending outwardly therefrom and abutting the bearing-blocks, means for locking said nut in position, and means for intermittently raising and lowering the standard as and for the purpose specified.
23. In a machine for the purpose specified the combination with the two pairs of corrugating-rollers having one movable roller in each pair, of bearing-blocks journaling the movable rollers, means for slidably supporting the same, a standard having an externally-screw-threaded top, a nut screwed on said top extending outwardly therefrom and abutting the bearing-blocks, means for locking said nut in position, a cam, and a roller secured to the bottom of the standard adapted to bear on the cam as and for the purpose specified.
24. An improved machine for forming flexible bands across sheets of paper comprising two pairs of corrugating-rollers, of which the second set is adapted to reverse the corrugations formed by the first, and means for holding the sheets of paper exactly in position while the second pair of rollers are operating on them whereby the corrugations formed by the first set, will be exactly reversed as and for the purpose specified.
25. An improved machine for forming flexible bands across sheets of paper consisting of means for producing a corrugated band across the sheet of paper in which the corrugation extends, longitudinally of the band, combined with means for exactly reversing each individual corrugation whereby the part forming the corrugation on one side will be stretched to form the corrugation on the opposite side, as and for the purpose specified.

Signed at the city of Ottawa, in the Province of Ontario, Canada, this 5th day of October, 1906.
